UNITED STATES PATENT OFFICE.

LEWIS D. NELSON, OF UNION CITY, MICHIGAN.

BAG-TYING MACHINE.

Application filed November 10, 1920. Serial No. 423,205.

To all whom it may concern:

Be it known that I, LEWIS D. NELSON, a citizen of the United States, residing at Union City, Branch County, State of Michigan, have invented certain new and useful Improvements in Bag-Tying Machines, of which the following is a specification.

This invention relates to improvements in bag tying machines.

10 The main objects of this invention are:

First, to provide an improved machine for tying bags, for example, cement bags, with wire ties;

15 Second, to provide an improved bag tying machine which has a large capacity;

Third, to provide an improved bag tying machine which is comparatively simple and compact in structure.

20 Further objects, and objects relating to structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing, forming a 30 part of this specification, in which:

Fig. I is a side elevation of a bag tying machine embodying the features of my invention, portions only of the frame being shown.

35 Fig. II is a detail plan view.

Fig. III is a detail plan view of the bag tying spindle and hooks at the end of the out-stroke of the spindle.

40 Fig. IV is a detail view partially in vertical section on a line corresponding to line 4-4 of Fig. II.

Fig. V is a detail section on a line corresponding to line 5-5 of Fig. IV, showing details of the tying hooks.

45 Fig. VI is a detail view partially in section on line corresponding to line 6-6 of Fig. I, showing details of the spindle actuating means.

Fig. VII is a detail vertical section showing 50 details of the tie feeding means, the feed member being shown in one position by full lines and in another position by dotted lines.

Fig. VIII is a detail plan view of the chute illustrating the position of the ties

therein and also prior to the removal of the 55 tie spooling wires.

In the drawing similar reference characters refer to similar parts throughout the several views, and the sectional views are taken looking in the direction of the little 60 arrows at the ends of the section lines.

Referring to the drawing, 1 represents the table bed upon which the machine is mounted. The operative parts are mounted upon the frame designated generally by the 65 numeral 2. However as the details of the frame form no part of this invention they are not further described herein.

I support the tying spindle 3 for rotative and longitudinal movement. On the front 70 end of this spindle are tying hooks or hooked fingers 4, the fingers being provided with superimposed disk-like portions 5 at their minor ends through which the pivot 6 is disposed, the pivot being carried by the head 75 7 on the front end of the spindle 3. The hooks are held open by means of the spring 8, which is supported by arranging in grooves in the opposite faces of the pivot, portions of the hooks, as shown in Figs. IV 80 and V, the ends of the spring being extended to engage the hooks as shown in Fig. V.

The hooks are held in their closed position by means of a catch which in the structure 85 illustrated comprises the barrel-like member 9 sleeved upon the head 7 of the spindle and provided with a pin 10 adapted to engage the notches 11 in the hooks when they are brought into register, a coiled spring 12 is arranged within the catch member to urge 90 it to engaging position. The catch member is provided with a lug 13 which engages the trip 14 on the frame on the return stroke of the spindle, thereby releasing the catch and allowing the spring 8 to open the hooks. 95 Adjustable stops 15 are provided for the hooks.

The spindle is returned by means of the spring actuated drum 16 connected to the rear end of the spindle by the cable 17 passing over the guide pulley 18. The ties 19 are fed to the hooks one by one with the eyes 20 at the ends of the ties engaging the hooks.

The bags 21 to be tied are placed behind 105 the tie as shown in Fig. II by the operator, and a forward pull on the bag closes the hooks and owing to the rotative movement

of the spindle twists the tie, as shown in Fig. III. The hooks are released by slipping the tie therefrom, and the spindle is retracted by the spring drum and the hooks are again 5 positioned to receive a tie.

To rotate the spindle as it is moved longitudinally I provide a tubular member 21 having a spiral slot 22 therein which is engaged by the pin 23 on the spindle. The 10 member 21 is supported in the barrel-like housing 24 mounted on a frame, the frame being provided with cross pieces 25 for supporting the same. The housing is adapted as a lubricant receptacle.

15 The feed chute of the structure illustrated comprises bars 26 and 27 spaced to provide slot-like ways 28 for the ties 19, the ties being arranged therein with their eyes at the outer sides of the bars. The chute is inclined forwardly so that the ties travel along the same by gravity. The bottom bars 26 are expanded at their forward ends and notched at 29 to receive the hooks the notches being V-shaped so that the hooks are guided to proper 20 position to receive the ties. The trip 14 of the hook catch is positioned so that the hooks are released and opened previous to the completion of the return movement of the spindle and the spindle rotating groove 25 is provided with a longitudinal portion 30 at its rear end—see Fig. VI—so that the hooks are supported with their bills in proper position to enter the notches during the final return movement of the spindle.

30 The ties are fed one by one, there being a feed means comprising spring stops 31 having downwardly turned ends 32 adapted to normally lie in the path of the ties. On the rock shaft 33 is a pair of feed members 34 adapted when the rock shaft is actuated to pass between the tie engaged with the stop members and the succeeding tie and to lift the stop members as shown by full lines in Fig. VII, thereby releasing the ties one by 35 one as the feed member is actuated. The rock shaft 33 is provided with an arm 35 connected by the link 36 to the lever 37 pivoted at 38 and positioned to be engaged by the tappet 39 on the spindle on the return 40 stroke of the spindle, thereby releasing or delivering a tie to the hooks on each return stroke. A coiled spring 40 is connected to the lever 37 so that on the forward stroke of the spindle the rock shaft is actuated to 45 retract the feed member allowing the ties to move down against the stop. The ties are ordinarily packaged in spools, the spooling wire 41 being arranged through the eye thereof. The spools are arranged on the 50 holder 42 and as the ties are required the spooling wires with the ties thereon are pulled along into the chute and the spooling wires cut off and withdrawn leaving the ties in the chute.

65 My improved tie machine has a very large

capacity, that is, it greatly increases the output of a workman over methods or devices heretofore employed. The bags are uniformly tied, all that is required of the workman being to see that the chute is supplied with 70 ties, to place the bags in the position shown in Fig. II and pull forwardly thereon. The structure illustrated is especially designed for tying bags such as cement bags in which the top is tied and the bags afterward filled 75 through a valve in the bottom. My improvements may, however, be readily adapted for use in various other relations. I have illustrated and described my improvements in an embodiment which I have found very 80 practical in use. I have not attempted to illustrate or describe certain modifications or adaptations which I contemplate, as I believe that the disclosure made will enable those skilled in the art to which my invention relates to embody or adapt the same as may be desired.

Having thus described my invention, what I claim as new and desire to secure by Letters Patent, is:

90 1. In a machine for tying bag ties having eyes at their ends, the combination of a spindle mounted for longitudinal and rotative movement, means for rotating said spindle as it is moved longitudinally, tie engaging 95 hooks, having disk-like superimposed portions at their inner ends pivotally mounted on said spindle, said disk-like portions being provided with notches registering when the hooks are closed, a catch member sleeved upon the end of said spindle and provided with a pin engaging said notches when they are in registering position, a spring urging said catch member to engaging position, a trip for releasing said catch member on the 100 return stroke of the spindle, a spring for opening said hooks, a feed chute comprising bars notched at their ends to receive the hooks when they are in their initial position so that the ties are delivered with their eyes 105 engaging the hooks, and a feed means for delivering the ties one by one.

110 2. In a machine for tying bag ties, the combination of a spindle mounted for longitudinal and rotative movement, means for 115 rotating said spindle as it is moved longitudinally, tie engaging hooks, pivotally mounted on said spindle, a spring for opening said hooks, a feed chute comprising bars down which the ties slide, said bars being inclined and notched at their ends to receive the hooks when they are in their initial position so that the ties are delivered with their eyes 120 engaging the hooks, and a feed means for releasing the ties one by one.

125 3. In a machine for tying bag ties having eyes at their ends, the combination of a spindle mounted for longitudinal and rotative movement, means for rotating said spindle as it is moved longitudinally, tie 130

engaging hooks having disk-like superimposed portions at their inner ends pivotally mounted on said spindle, said disk-like portions being provided with notches registering when the hooks are closed, a catch member sleeved upon the end of said spindle and provided with a pin engaging said notches when they are in registering position, a spring urging said catch member to engaging position, a trip for releasing said catch member on the return stroke of the spindle, and a spring for opening said hooks.

4. In a machine for tying ties the combination of a spindle mounted for longitudinal and rotative movement, means for rotating said spindle as it is moved longitudinally, means for retracting said spindle, tie engaging hooks pivotally mounted on said spindle, a catch for holding said hooks in closed positions, a trip for releasing said catch member on the return stroke of the spindle, and a spring for opening said hooks.

5. In a machine for tying bag ties having eyes at their ends, the combination of a spindle mounted for longitudinal and rotative movement, means for rotating said spindle as it is moved longitudinally comprising a cylinder through which the spindle is disposed having a spiral slot therein terminating at its rear end in a longitudinally disposed portion and a pin on said spindle engaging said slot, means for retracting said spindle, tie engaging hooks pivotally mounted on said spindle, a spring for opening said hooks, a feed chute comprising bars notched at their ends to receive the hooks when they are in their initial position so that the ties are delivered with their eyes engaging the hooks, and a feed means for delivering the ties one by one.

6. In a machine for tying bag ties having eyes at their ends, the combination of a spindle mounted for longitudinal and rotative movement, means for rotating said spindle as it is moved longitudinally comprising a cylinder through which the spindle is disposed having a spiral slot therein terminating at its rear end in a longitudinally disposed portion and a pin on said spindle engaging said slot, means for retracting said spindle, tie engaging hooks, pivotally mounted on said spindle, a spring for opening said hooks, and a feed chute comprising bars notched at their ends to receive the hooks when they are in their initial position so that the ties are delivered with their eyes engaging the hooks.

7. In a machine for tying bag ties having eyes at their ends, the combination of a spindle mounted for longitudinal and rotative movement, means for rotating said spindle as it is moved longitudinally, means for retracting said spindle, tie engaging hooks pivotally mounted on said spindle, a spring actuated catch on said spindle for holding said hooks in their closed position, a trip for

releasing said catch on return stroke of the spindle, a spring for opening said hooks, a feed chute comprising bars notched to receive the hooks when they are in their initial position so that the ties are delivered with their eyes engaging the hooks, and a feed means for the ties including said spindle as an actuating member.

8. In a machine for tying bag ties having eyes at their ends, the combination of a spindle mounted for longitudinal and rotative movement, means for rotating said spindle as it is moved longitudinally, tie engaging hooks pivotally mounted on said spindle, a spring actuated catch on said spindle for holding said hooks in their closed position, a trip for releasing said catch on return stroke of the spindle, a spring for opening said hooks, and a feed chute comprising bars notched to receive the hooks when they are in their initial position so that the ties are delivered with their eyes engaging the hooks.

9. In a machine for tying bag ties having eyes at their ends, the combination of a spindle mounted for longitudinal and rotative movement, means for rotating said spindle as it is moved longitudinally, means for retracting said spindle, tie engaging hooks pivotally mounted on said spindle, a spring for opening said hooks, a feed chute comprising bars down which the ties slide, said bars being inclined and notched to receive the hooks when they are in their initial position so that the ties are delivered with their eyes engaging the hooks, and means for successively releasing the ties in said chute including said spindle as an actuating member.

10. In a machine for tying bag ties, having eyes at their ends, the combination of a spindle mounted for longitudinal and rotative movement, means for rotating said spindle as it is moved longitudinally, tie engaging hooks pivotally mounted on said spindle, a spring for opening said hooks, and a feed chute comprising bars down which the ties slide, said bars being inclined and notched to receive the hooks when they are in their initial position so that the ties are delivered with their eyes engaging the hooks.

11. In a machine for tying bag ties, the combination of a spindle mounted for longitudinal and rotative movement, means for rotating said spindle as it is moved longitudinally, tie engaging hooks pivotally mounted on said spindle, a spring actuated catch on said spindle for holding said hooks in their closed position, a trip for releasing said catch on return stroke of the spindle, and a spring for opening said hooks.

12. In a machine for tying bag ties having eyes at their ends the combination of a spindle mounted for longitudinal and rotative movement, means for rotating said spindle as it is moved longitudinally, means

for retracting said spindle, tie engaging hooks pivotally mounted on said spindle, a feed chute comprising pairs of spaced bars providing slot-like ways for the ties disposed in the chute with their eyes at the outer sides of the bars, the front ends of the bottom bars of the chute being flared outwardly and notched to receive the hooks when they are in their initial position so that 5 the ties are delivered with their eyes engaging the hooks, a spring stop member for the ties disposed between the pairs of chute bars, and a feed member pivotally mounted to swing upwardly between the tie engaged by 10 the stop and the succeeding tie, and adapted to lift the stop thereby delivering the ties to said hooks one by one.

13. In a machine for tying bag ties having eyes at their ends, the combination of a 20 spindle mounted for longitudinal and rotative movement, means for rotating said spindle as it is moved longitudinally, means for retracting said spindle, tie engaging hooks pivotally mounted on said spindle, a feed chute comprising bottom bars notched to receive the hooks when they are in their initial position so that the ties are delivered 25

with their eyes engaging the hooks, a stop member for the ties, a feed member mounted to swing between the tie engaged by the 30 stop and the succeeding tie, and adapted to lift the stop thereby delivering the ties to said hooks one by one, and an actuating means for said feed member comprising a tappet on said spindle. 35

14. In a machine for tying bag ties having eyes at their ends, the combination of a spindle mounted for longitudinal and rotative movement, means for rotating said spindle as it is moved longitudinally, means for retracting said spindle, tie engaging hooks pivotally mounted on said spindle, a feed chute comprising bottom bars notched to receive the hooks when they are in their initial position so that the ties are delivered 40 with their eyes engaging the hooks, a stop member for the ties, and a feed member mounted to swing between the tie engaged by the stop and the succeeding tie, and adapted to lift the stop thereby delivering the ties to said hooks one by one. 45

In witness whereof, I have hereunto set my hand and seal.

LEWIS D. NELSON. [L.S.]
